CARL MUEHLEISEN, OF BERLIN, GERMANY, ASSIGNOR TO MERGENTHALER LINOTYPE COMPANY, A CORPORATION OF NEW YORK.

DISTRIBUTING MECHANISM OF TYPOGRAPHICAL COMPOSING AND CASTING MACHINES.

1,139,704.

Specification of Letters Patent. Patented May 18, 1915.

Application filed July 23, 1914. Serial No. 852,542.

To all whom it may concern:

Be it known that I, CARL MUEHLEISEN, a citizen of the United States of America, residing at 23 Chausseestrasse, Berlin, N. 4, 5 in the Empire of Germany, have invented new and useful Improvements in the Distributing Mechanism of Typographical Composing and Casting Machines, of which the following is a specification.

10 This invention relates to improvements in the distributing mechanism of typographical composing and casting machines, such, for example, as those known commercially under the trade mark "linotype," employing 15 matrices which are stored in a magazine, released from that magazine and assembled in order of composition, presented in that order to a casting mold and, after the casting operation, conveyed to a distributing mechanism by means of which they are restored each to its respective channel of the magazine. Such matrices, as is well known, are provided with distributing teeth of approximately uniform thickness, irrespective 20 of the set-wise dimensions or body thickness of the matrices themselves, and they are also provided at the top and bottom of each vertical edge, with projecting lugs, which, in many cases are of a thickness considerably 25 less than the set-wise dimension of the matrices. Further, the distributing teeth and the lugs are respectively situated at opposite sides of the above-named vertical edges.

30 During part of the distributing operation, just before the distributing teeth on the matrices engage with the ribs on the distributor rail, the matrices travel along a pair of guide rails, on which they are suspended by their upper lugs; and, when so suspended, those matrices which have a set-wise dimension appreciably greater than the thickness of the lugs, have a tendency to swing into an oblique position, owing to the 35 center of gravity not being in the same plane as the supporting lugs. It is essential, however, for enabling the distributing teeth of the matrices to engage with the ribs of the distributor rail, that they should be 40 maintained in a vertical or substantially vertical position during the time that they are suspended on the guide rails, and the

object of the present invention is to provide means for effecting such maintenance of 55 verticality.

The invention will now be described with reference to the accompanying drawings throughout the several figures of which like reference numerals are used to indicate like or corresponding parts, and in which:— 60

Figure 1 is a rear elevation of part of a distributing mechanism, illustrating one constructional form of the invention; Fig. 2 is a front elevation of part of a distributing mechanism, illustrating another constructional form, and Figs. 3, 4, 5, 6, 7 and 8 are side elevations showing respectively 65 different methods of supporting the matrices.

Throughout this specification and in the 70 drawings, the invention is described and illustrated as applied to a distributing mechanism provided with a device already known in the art, as a "separator box." In this separator box 1 (see Fig. 2), the matrices 75 which have previously entered at the top, as shown by the one marked 2 in that figure, form into an inclined row, the successively leading matrices of which are separated from the following ones by the finger 3, which is reciprocated in alternation with 80 the companion finger 4, which serves to hold the advancing row in check at the time that it is not so held by the finger 3, these fingers 3 and 4 being oscillated in well known manner by the rocking levers 6 and 7 respectively.

Referring now to Figs. 1, 8 and 8^a are two guide rails, one (8) being situated behind and the other (8^a) in front of the 90 known distributor rail 12. 10 is a thick matrix which has been delivered on to the guide rails 8, 8^a, from the separator box, and which is suspended from those guide rails by its upper lugs 11. While the matrix 95 10 is thus suspended from the guide rails 8, 8^a, it is moved toward the distributor rail 12 by the engagement of its two upper lugs 11 and one of its lower lugs 13 with the three known distributor screws (only one of 100 which, viz.—the lower one, 14, is shown in the drawing), until its distributing teeth 15 (see particularly Figs. 3 to 8) engage with the ribs on the distributor rail 12. The rails

8, 8^a, terminate at a point just beyond that at which the last mentioned engagement has been effected, beyond which point the matrices, of course, no longer rely for support upon their upper lugs, which thereafter are only engaged with the two upper distributor screws. As previously stated, it is during the just-described part of the distributing operation, at which a thick matrix 10 is suspended on the guide rails 8, 8^a, by its upper lugs 11 that the mischievous swinging of that matrix takes place. According to the modification represented in Fig. 1, this swinging is prevented by thickening the thread of the lower distributor screw 14 on the following side of that thread, as indicated at 16, over that portion of the screw which engages a lower matrix lug 13, during the time at which the upper lugs 11 are traveling along the guide rails, 8, 8^a, so that at that part the groove of the screw is only of sufficient width to receive the said lower lug without admitting of any appreciable movement thereof, between the two adjacent convolutions of the thread. The matrix 10 is thus kept in a vertical position until its distributing teeth 15 engage with the ribs of the distributor rail 12, the thickened thread continuing along the screw 14 only so far as is necessary to insure such engagement being effected, the thread beyond that point being of the usual known form. It is obvious that this thickening of the thread does not affect the pitch of the screw (an alteration which has already been proposed for a different purpose), and consequently the synchronous working of the three distributor screws is not thereby disturbed.

According to the constructional form of the invention illustrated in Fig. 2, an additional support for the matrices is provided in the form of a rail 17, in such a position that the traveling matrices 10 will contact with it during the time at which they are suspended by their upper lugs 11 from the guide rails 8, 8^a, such contact continuing only so long as is necessary to insure the distributing teeth 15 engaging with the ribs on the distributor rail 12. The support 17 is arranged to contact with the matrix 10 in any suitable manner, for instance, it may, as shown in Figs. 2 and 3, contact with the foot of the matrix, either under the lug which is not in engagement with the lower distributor screw, or symmetrically beneath the foot, as shown in Fig. 4; or it may engage a notch in the matrix, situated in any convenient position; for example, in the foot as shown in Fig. 5, above one of the lower lugs as shown in Fig. 6, or in one of the edges of the matrix either closely under one of the upper lugs as shown in Fig. 7, or in a lower position as shown in Fig. 8.

Having described my invention, I declare

that what I claim and desire to secure by Letters Patent is:—

1. In the distributing mechanism of a typographical composing and casting machine, the combination with a pair of guide rails adapted to support matrices by engaging under their upper lugs, matrices which, when so supported, unless prevented from so doing, would hang in an oblique position, a distributor rail adapted to receive matrices from the guide rails and suspend them by their distributing teeth, and means adapted to propel matrices along the said guide rails and distributor rail, of a means adapted to keep the matrices in a substantially vertical position during the time at which they are suspended from the guide rails.

2. In the distributing mechanism of a typographical composing and casting machine, the combination with a pair of guide rails adapted to support matrices by engaging under their upper lugs, matrices which, when so supported, unless prevented from so doing, would hang in an oblique position, distributing teeth on the matrices, a distributor rail having ribs for the engagement therewith of the distributing teeth of the matrices and distributor screws adapted to propel matrices along the guide rails and distributor rail, of means to engage the matrices and keep them in a substantially vertical position during the time at which they are suspended from the guide rails.

3. In the distributing mechanism of a typographical composing and casting machine, the combination with a pair of guide rails adapted to support matrices by engaging under their upper lugs, matrices which, when so supported, unless prevented from so doing, would hang in an oblique position, distributing teeth on the matrices, a distributor rail having ribs for the engagement therewith of the distributing teeth of the matrices, a distributor screw adapted, by engagement with their upper lugs, to propel matrices along the guide rails and distributor rail, of a distributor screw adapted to engage one of the lower lugs of each such matrix, said screw having its thread thickened at the part which engages such lower lug during the time at which the upper lugs are traveling over the guide rails.

4. In the distributing mechanism of a typographical composing and casting machine, the combination with matrices adapted to be propelled through the distributing mechanism, of a distributor screw adapted to so propel the matrices, having part of its thread at its receiving end of one thickness and the remaining part of its thread of less thickness.

5. In the distributing mechanism of a typographical composing and casting ma-

chine, the combination with matrices adapted to be propelled through the distributing mechanism, of a distributor screw adapted to so propel the matrices, having part of its 5 groove at its receiving end of one width and the remaining part of its groove of a greater width.

6. In a typographical machine comprising matrices, each formed at its upper end 10 with lugs projecting from its opposite edges and located to one side of its center of gravity, the combination of a pair of guide rails along which the matrices are carried and upon which they are suspended at their 15 opposite edges by their projecting lugs, and means to engage the matrices throughout their travel along the rails and hold their free or lower ends against swinging or tilting.

20 7. In a typographical machine comprising matrices formed at their upper ends with projecting lugs located to one side of their center of gravity, the combination of

distributing mechanism, guiding means leading thereto and upon which the matrices are supported by their upper lugs, and means to engage the matrices when so supported and maintain them in a vertical position.

8. Distributing mechanism for typographical machines comprising a distributor bar along which the matrices travel, and a conveying screw having a spiral groove wherein the projecting lugs of the matrices engage, the said groove being of such width 30 as to embrace closely the projecting lugs of the type or matrices; whereby the latter are prevented from swinging or tilting in their travel.

In witness whereof I have hereunto set 40 my hand in the presence of two witnesses.

CARL MUEHLEISEN.
